UNITED STATES PATENT OFFICE.

FREDERICK WOOD, OF LIVERPOOL, ENGLAND.

FOLDING BEDSTEAD.

No. 851,724.

Specification of Letters Patent.

Patented April 30, 1907.

Application filed February 20, 1905. Serial No. 246,451.

To all whom it may concern:

Be it known that I, FREDERICK WOOD, a subject of the King of Great Britain and Ireland, residing at No. 55 Upper Hope Place, Liverpool, England, have invented 5 a new and useful Improvement in Folding Bedsteads, of which the following is a specification.

The present invention relates to folding 10 or collapsible bedsteads, for military uses, camping, and general purposes.

A bedstead according to this invention 15 comprises four uprights connected by two folding end-frames and two folding side frames. The construction of said side and end frames is such that when the bedstead is erected they form with the said uprights a rigid structure, and may be folded so as to occupy small space when the bedstead is 20 taken down. A bed-sheet is stretched between the heads of the said four uprights, and means are provided for stretching such sheet.

Reference to the annexed drawings. Fig. 25 ure 1 is a perspective view, and Fig. 2 is a side elevation of a bedstead constructed according to this invention. Fig. 3 illustrates the same bedstead partly folded. Fig. 4 is a plan of the bedstead, and Fig. 5 30 is an end elevation of the same. Figs. 6 and 7 are two views showing the bedstead when it is folded for transport or storage.

The improved bedstead comprises the 35 four posts A, the two side rails B, and certain jointed stay-rods which are hereinafter referred to. The bed proper is formed by the canvas or similar sheeting C, the ends of which are attached to the rollers D, E. Each side rail B is rule-jointed at F, the ends 40 of the rails being pin-jointed to the posts A. Connecting the said rule-joints F with the posts A are jointed stays which comprise two members, G and H, a projection g on the member G overlapping the member H, 45 whereby the said members form a knuckle-joint. The ends of the bedstead are formed by diagonal stays, each of which comprises two members, J and K, a projection j on the member J overlapping the member K, where- 50 by said members form a knuckle-joint. On the heads of the posts A are slotted socket pieces L, which receive the pins d, e, in the ends of the rollers D, E, and attached to these rollers is the bed-sheet C. A pawl M

engages a ratchet N on the bottom roller E, 55 so that the bed-sheet may be kept in tension.

When the two halves of the side-rails B are opened out into alinement with each other, and the two halves G, H, and J, K, of the side and end stays are similarly placed 60 in alinement, it will be seen that these side rails and side and end stays and the four posts to which they are all jointed, form a rigid structure, ready to receive the end rollers of the bed-sheet and to bear the weight of the 65 occupant. When the bed is occupied, the posts A become levers of the first order, the side rails B forming the fulcrum while the stays G, H, are subjected to tension.

To fold or collapse the bedstead, the bed- 70 sheet C and its rollers are first removed. The knuckle-joints of the end stays J, K, are then 'broken' to permit of the two sides of the bedstead being laid against one another. The knuckle-joints of the side rails B and 75 side stays G, H, are then similarly 'broken' so as to permit of the posts A assuming the position shown in Fig. 2, and of ultimately being laid in alinement with the side rails B as shown in Figs. 6 and 7, in which figures 80 is shown the bedstead as folded into its smallest compass.

The posts A and side rails B are preferably 85 tubular. The said posts are provided with feet O, and projecting from these feet—at right angles—are pins a, b, which receive the stays G and K and are then riveted over. Collar pieces P are shrunk or otherwise fixed upon the posts A and possess pins p, q, at 90 right angles to one another, which pins receive the side rails B and stays J and are then riveted over.

X is a mosquito curtain frame which is stepped in the sockets Y.

Having now described my invention, what 95 I claim as new and desire to secure by Letters Patent is:—

A bedstead comprising uprights A, and side members B jointed at F, stays H, G, flexing in one direction and connecting the 100 joint F with the feet of the members A, and stays J, K flexing in one direction and connecting the feet O of the members A with the collars P on the opposite members.

FREDERICK WOOD.
